UNITED STATES PATENT OFFICE.

HENRY ROOT, OF SAN FRANCISCO, CALIFORNIA.

DESIGN FOR A TOOL.

SPECIFICATION forming part of Design No. 31,941, dated December 5, 1899.

Application filed October 11, 1899. Serial No. 733,322. Term of patent 14 years.

To all whom it may concern:

Be it known that I, HENRY ROOT, a citizen of the United States, residing at the city and county of San Francisco, State of California, 5 have invented and produced a new and original Design for Tools, of which the following is a specification, reference being had to the accompanying drawings, forming part thereof.

Figure 1 is a front view of a tool, showing 10 my new design. Fig. 2 is an edge view of same. Fig. 3 is a perspective view of same.

The material feature of my design is the ax-like head A in line with the crowbar-like handle B, the butt of the ax-like head join-

ing the point or foot of the crowbar-like 15 handle.

Having described my invention, what I claim as new, and desire to secure by Letters Patent, is—

The design for a tool, substantially as herein shown and described.

In witness whereof I have hereunto set my hand.

HENRY ROOT.
